DESIGN FOR AN ASH TRAY

Harry G. Shaughnessy, Detroit, Mich.

Application May 27, 1941, Serial No. 191,186

Term of patent 3½ years

To all whom it may concern:

Be it known that I, Harry G. Shaughnessy, a citizen of the United States residing at Detroit, in the county of Wayne and State of Michigan, have invented a new, original, and ornamental Design for an Ash Tray, of which the following is a specification, reference being had to the accompanying drawing, forming part thereof, wherein:

Fig. 1 is a top plan view of an ash tray showing my new design.

Fig. 2 is a side elevational view of same.

Fig. 3 is a perspective view of the ash tray.
I claim:

The ornamental design for an ash tray, as shown.

HARRY G. SHAUGHNESSY.
